PERCUSSIVE TOOL

William A. Smith, Sr., Athens, Pa., assignor to
Ingersoll-Rand Company, New York, N. Y., a
corporation of New Jersey

Application March 20, 1941, Serial No. 384,256

2 Claims. (Cl. 125—33)

This invention relates to percussive tools, and more particularly to a percussive tool driven mechanically through suitable devices and connections by an individual power element.

One object of the invention is to construct a rugged and compact percussive tool that may be conveniently manipulated and guided with respect to the work and which will be capable of delivering forceful blows at a rapid rate of speed to the working implement intended to be actuated by the percussive tool.

Another object is to enable the power element of the percussive tool to be conveniently and expeditiously connected to and disconnected from the percussive element.

Other objects will be in part obvious and in part pointed out hereinafter.

In the drawing accompanying this specification and in which similar reference numerals refer to similar parts,

Figure 1 is an elevation, partly in section of a percussive tool constructed in accordance with the practice of the invention,

Figure 2 is a transverse view taken through Figure 1 on the line 2—2,

Figure 3 is a side view of a detail partly broken away, and

Figure 4 is a transverse view taken through Figure 1 on the line 4—4.

Referring more particularly to the drawing, 20 designates, in general, a percussive tool and 21 a working implement which the percussive tool is intended to actuate.

In the form of the invention illustrated, the percussive tool comprises a crank casing 22 having an end surface 23 serving as a seat for a support member 24 which may be secured to the crank casing 22 in any suitable manner. The support member 24 is hollow to receive a rod 25 of a length to project from the ends of the support member for the accommodation of hollow grip members 26 that may be grasped for manipulating the tool and guiding it with respect to the work.

In the front end of the crank casing is an enlarged recess 27 to receive the end of a cylinder 28, the opposite end of which is suitably attached to a front head 29 containing a bushing 30 for guiding the working implement 21. Within the cylinder 28 is a percussive element designated 31 in its entirety, by 31 and comprising a hollow plunger 32 which is sealed at its rearward end by a plug 33 press-fitted therewith and has a hollow extension 34 of reduced diameter at its front end. The plunger 32 has a nice sliding fit

in the cylinder 28, and in the interior or chamber 35 of the plunger is a reciprocating piston 36 having a reduced stem 37 extending slidably through the hollow extension 34 to strike against the working implement 21.

As a preferred arrangement, the plunger 32 is provided with an annular groove 38 in its periphery and in the wall of the plunger, at points located suitable distances from the rear and front ends of the chamber 35, are ports 39 and 40, respectively, to afford communication between the annular groove 38 and the interior of the plunger. The portions of the chamber 35 lying rearwardly of the ports 39 and forwardly of the ports 40 constitute cushioning chambers 41 and 42, respectively, wherein atmospheric air will be entrapped to form a cushion between the piston 36 and the end surfaces of the chamber 35.

The plug 33 is recessed to receive the end of a connecting rod 43 and a wrist pin 44 extending through the connecting rod is press-fitted into the plug 33 and the plunger 32 to lock the plug securely to the plunger. The connecting rod 43 lies in the chamber 45 in the crank casing 22 and is connected at its other end to a crank pin 46 on the web 47 of a crank shaft 48 extending through a side wall 49 of the crank casing 22. The connecting rod may be retained on the crank pin 46 in any suitable manner, as for example by a washer 50 held in position by a nut 51 threaded on the end of the crank pin. An anti-friction bearing 52 in the wall 49 supports the shaft 48 adjacent the web 47, and the shaft extends through a gear chamber 53 on the side of the crank casing and is supported by a cover 54 forming a closure for the gear chamber 53 and secured to the casing 22 by bolts 55.

The portion of the shaft 48 lying outside of the anti-friction bearing 52 is of somewhat reduced diameter and on it is arranged, for free rotation on the shaft, a driving gear 56 which abuts the anti-friction bearing 52 and contains a series of rollers 57 to minimize friction between the gear and the shaft. The gear 56 is restrained against endwise movement in the direction of the cover 54 by an inner surface 58 on the cover 54 lying directly in front of the gear.

The gear 56 is shown as being of the spur type and its teeth mesh with a driving pinion 59 having trunnions 60 and 61 that extend, respectively, into the wall 49 and the cover 54 and are provided with anti-friction rollers 62 and 63. The pinion and the trunnions are hollow, having a bore 64 of polygonal shape to receive a correspondingly shaped end 65 of a flexible cable

66 having its other end connected to a prime mover (not shown) as for example an internal combustion engine or an electrical motor. A conduit 67 enclosing the cable 66 is threadedly connected to a bushing 68 in the cover 54 and abutting the trunnion 61.

Suitable means are provided for holding the gear 56 fixedly with respect to the shaft 48 whenever it is intended to actuate the percussive element 31. To this end the gear 56 is provided, in the side confronting the cover 54, with an annular recess 69 having a coniform surface 70 for frictional engagement with a clutch member 71. The clutch member is slideable longitudinally upon the shaft 48 and is held against rotary movement with respect to the shaft by a key 72 seated in the shaft and extending into a key slot 73 in the clutch member.

In the form of the invention illustrated, force is applied to the clutch member 71 for actuating it by a lever 74 overlying the grip member 26 and being pivotally connected to a pin 75 in the support member 24. The pin 75 lies beneath the rod 25 and on the adjacent portion of the lever is a wing 76 to seat upon the head 77 of a plunger 78 slideable in the cover 54. A spring 79 is interposed between the head 77 of the plunger and the cover to normally hold the plunger in retracted position and thus to hold the lever 74 in readiness for depressing the plunger.

The opposite or lower end 80 of the plunger extends into the bore 81 of the cover 54 to engage a radial shoulder 82 in the periphery of a thrust member 83 seated in the bore 81. The thrust member 83 is rotatable in the bore 81 and its interior surface serves as a bearing for the outer end of the shaft 48, or, more particularly, for rollers 84 arranged about the end of the shaft.

The thrust member 83 is provided on its periphery with a flange 85 to seat against a shoulder 86 in the bore 81 for preventing movement of the thrust member in an outwardly direction, and on the inner surface of the thrust member are a plurality of grooves 87 to accommodate balls 88 serving to translate the rotary movement of the thrust member into longitudinal movement of the clutch member 71. The grooves 87 are all described on the same circle and of gradually decreasing depth from an end 89 which is suitably shaped to conform to the curvature of a ball 88.

Interposed between the thrust member 83 and the clutch member 71 is a plate 90 which is slideable freely in the bore 81 and held against rotary movement by diametrically opposed lugs 91 on its periphery extending into grooves 92 in the bore 81. In the side of the plate 90 confronting the inner end of the thrust member 83 are grooves 93 of the same conformation as the grooves 87, although reversed so that their shallow ends point in the same direction as the deep ends 89 of the grooves 87.

The plate 90 is so positioned with respect to the thrust member 83 that the balls 88 will lie in both the grooves 87 and the grooves 93, and on the opposite side of the plate 90 is an anti-friction bearing 94 to transmit the thrust of the member 83, as transmitted by the balls 88 and the plate 90, to the clutch member 71.

Means are provided to automatically rotate the thrust member 83, to follow the plunger 78 upon release of the lever 74 and thus to permit the immediate release of the clutch member 71 from the gear 56 whenever it is intended to discontinue the delivery of blows to the working implement 21. To this end the thrust member

83 is provided in its periphery with a second radial shoulder designated 95 and preferably positioned diametrically opposite the shoulder 82. The shoulder 95 serves as a seat for a plunger 96 slideable in a bore 97 in the cover 54 and pressed against the shoulder 95 by a spring 98 interposed between the plunger and a plug 99 threaded into the outer end of the bore 97.

The operation of the device is as follows: 10 Whenever it is intended to actuate the working implement 21, and assuming of course that the gear 56 is being rotated, the lever 74 is rocked about the pivot 75 for pressing the plunger 78 downwardly. This movement of the plunger 15 causes the thrust member 83 to be rotated about the shaft and the balls 88 to be shifted toward the shallow ends of both the grooves 87 and 93.

In assuming the described position the balls 88 will shift the plate 90, the thrust bearing 94 and 20 the clutch member 71 inwardly along the shaft 48 and force the clutch member into frictional engagement with the coniform surface 70. Inasmuch as the clutch member 71 is interlocking engaged with the shaft 48 the shaft will 25 then rotate with the gear and cause the plunger 32 to be reciprocated in the cylinder 28.

During the downward movement of the plunger the piston 36 will be in its rearmost limiting position and when the plunger reaches the lowermost limit of its movement the piston is impelled 30 forwardly to strike against the working implement 21. On this stroke of the piston the air in the cushioning chamber 42 will be compressed after the piston covers the ports 40 but not to 35 such an extent as to seriously diminish the force of the blow of the piston.

During the rearward stroke of the plunger the piston 36 will be retracted from the working implement and will be impelled into the rearward end of the chamber 35 at the instant of reversal of the plunger. The piston will, however, be prevented from striking the plug 33 by the air entrapped in the cushioning chamber 41 and will remain in its rearmost limiting position relatively to the plunger during the forward movement of the latter. Upon the subsequent reversal of the plunger the piston will continue in a forwardly direction and strike heavily against the working implement. This cycle of operation may be continued as long as the clutch member remains in engagement with the surface 70.

Upon completion of the drilling operation, or if for another reason it should be desired to discontinue the application of blows to the working implement, the pressure against the lever 74 is released. The spring 79 will then retract the plunger 78 and thereby remove the pressure against the shoulder 82 of the thrust member 83. At the same time the spring-pressed plunger 96 will rotate the thrust member 83 to its initial position and the parts serving to transmit movement from the thrust member to the clutch member 71 for engaging the gear 56 may then adjust themselves to their original positions. In this way the frictional engagement between the clutch member and the coniform surface 70 will be broken and the percussive element will come to rest.

I claim:

1. A percussive tool, comprising a casing having a handle, a reciprocatory percussive element in the casing, a crank shaft in the casing, means for transmitting movement from the crank shaft to the percussive element, a gear freely rotatable on the crank shaft, a pinion for driving the gear,

a conical surface on the gear, means slidably interlocked with the crank shaft to frictionally engage the conical surface for connecting the gear to the crank shaft, thrust means for moving the last mentioned means into engagement with the conical surface, a bearing in the thrust means for the crank shaft, a spring pressed plunger for actuating the thrust means, and a lever on the handle for actuating the plunger.

2. A percussive tool, comprising a casing hav-

ing a handle, a reciprocatory percussive element in the casing, a crank shaft in the casing for actuating the percussive element, means for driving the crank shaft, a pair of clutch members for effecting a driving connection between the driving means and the crank shaft, thrust means for actuating one clutch member with respect to the other clutch member, and a bearing in the thrust means for the crank shaft.
